United States Patent Office

Des. 228,809

Patented Oct. 23, 1973

228,809

MICROFICHE VIEWER

John L. Jones, Gardena, Calif., assignor to UMF
Systems Incorporated, Los Angeles, Calif.

Filed Feb. 18, 1972, Ser. No. 227,701

Term of patent 14 years

Int. Cl. D16—02

U.S. Cl. D61—1 N

FIG. 1 is a front and right side perspective view of a microfiche viewer showing my new design; and

FIG. 2 is a front and left side perspective view thereof, the rear being plain and unornamented.

I claim:

The ornamental design for a microfiche viewer, substantially as shown and described.
